UNITED STATES PATENT OFFICE

2,020,532

HEAT TRANSFER UNIT

Fred M. Young, Racine, Wis.

Application June 30, 1933, Serial No. 678,348

3 Claims. (Cl. 248—142)

My invention relates to heat transfer units suitable for heating automobiles, wherein the cooling liquid from the engine is used for heating a fan motor directed air current and wherein this unit is positioned a short distance rearwardly from the cowl board and is held thereto by means of two novel supporting brackets having a shape to thereby provide novel supporting means for the fan motor.

10 It is the intention that the present patent shall cover, by suitable expression, in the appended claims, features of patentable novelty, other than claimed in my divisional application, as described in the specification executed by me this 14th day

15 of December 1933.

The object of my invention is to simplify the device, make it more convenient for installation, efficient in operation, more durable and to avoid the constant annoyances caused by loosened parts, etc., to which units of this class are subjected.

I accomplish these various objects by the use of novel unitary holding brackets which are formed from flat stock and by providing means whereby the fan motor may be removed without disturbing the unit or the brackets, and whereby the unit may be removed without disturbing the brackets or motor.

To these and other useful ends this invention 30 consists in matter hereinafter described and claimed and shown in the accompanying drawings in which:

Figure 1 is a side elevation of a car heating radiator equipped with my invention.

35 Figure 2 is a front elevation of the radiator and brackets shown in Figure 1.

Figure 3 is a top plan view illustrating the supporting brackets, fan motor and air directing means.

40 Figure 4 is a fractional rear view of the unit showing the air directing means in the position illustrated in Figure 1.

As thus illustrated, 10 designates the core of the radiator comprising the usual tubes and fins, 45 11 and 12 designate the usual headers having reinforcing plates 15 which supply a suitable wall for openings into which to attach the pipes 13 and 14 which are suitably connected to the liquid cooling system of the engine. The plates 15 and pipe connections are, as clearly illustrated in Figures 1 and 2, positioned on the front of the headers and in the center thereof. In the plates 15 and on opposite sides of the pipe connections I 50 provide threaded openings as at 16, thus supply-

ing means for securing the supporting brackets to the headers, as will hereinafter appear.

The usual practice is to attach the heating unit to the vertically positioned cowl board of the automobile providing room therebetween for the 5 fan motor which in the drawings is illustrated as an electric motor and designated by number 17.

I provide two unitary brackets made from flat stock and formed to thereby supply supporting means for the fan motor 17 and the heating unit, 10 which in its entirety is designated by reference character A.

The upper bracket differs somewhat from the lower bracket and is in its entirety designated by reference character B. The lower bracket is des- 15 ignated by reference character C.

Referring now to bracket B, the rear end of which has an upwardly extending gusseted projection or foot 20. This foot is provided with an opening 21 for pipe 14. Openings are supplied 20 which register with the threaded openings in the reinforcing plate 15 whereby the bracket is secured to the plate by means of bolts or screws as at 16.

The main body of the bracket B extends for- 25 wardly, having an abrupt downward bend as at 22 forming vertically positioned gusseted projections or feet 23 and 24, a strip of material having been removed to thereby provide these spaced apart feet, as clearly indicated in Figures 2 and 3. 30 Orifices 25 are provided to thus supply means for attaching these feet to the cowl board of the car.

The arm 26 is cut from the body of the bracket B and bent downward to thereby form a suitable upper support for the fan motor 17, the end of 35 which is made fast to the motor bracket as at 27. In this design it will be seen by scrutinizing the various views, that the material is suitably ribbed and flanged to thereby add to the strength and rigidity of the bracket.

40 The bracket C is similar to bracket B, except at its front end one foot only is preferably provided, thus to supply a three-point support at the cowl board for the unit A, and further by dispensing with one foot, the motor can be conveniently re- 45 moved from the assembly. In bracket C, numeral 30 designates the rear foot. The opening for pipe 13 is designated by numeral 31. This rear foot is attached to the plate 15, as at 16, similar to bracket B. The bracket C is bent as at 32, 50 the part 33 extending rearwardly and upwardly and is bent again as at 34 providing a vertically positioned gusseted foot 35 having an opening as at 36 with which to be attached to the vertical cowl board of the car.

The arm 37 is cut from the body of bracket C similar to arm 26 of bracket B and is shaped similarly to thereby provide a bottom support for the motor 17 which is connected to the motor bracket 5 as at 38.

For some installations it may be found desirable to use bracket B as the bottom support instead of bracket C or vice versa. Applicant therefore does not wish to be limited to either combination.

Thus it will be seen that the supporting brackets are light, strong, rigid and inexpensive, that the motor can easily be removed without disturbing any other part of the assembly and that the 15 heating unit A may be removed without disturbing the motor or the brackets.

It will further be seen that by supporting the motor direct to the brackets by means of the arms 26 and 37, the unit A fastenings to the 20 brackets are relieved of the weight of the motor and that the two brackets are interconnected through the motor in a way which will add to their strength and rigidity.

I have thus described my novel means for supporting the radiator unit and the fan motor therefor. The fan is adapted to force air through the core of the radiator but, for various reasons, the operator may wish to direct the heated air as it 25 leaves the core. I provide novel means whereby 30 the air stream may be diverted in any desired direction in the following manner:

A decorative housing 40 is provided and assembled over the front edge of the core and headers and having a central bar 41 formed preferably 35 as an integral part of the housing. This bar is provided with a centrally positioned bolt 42, a spring 43 and nut 44. A flat arm 45 is rotatably mounted at one end on the bolt 42 and positioned under the spring 43 which is heavy enough to hold 40 the arm in a fixed position unless moved manually. The bar 41 has a streamline or air foil shape in direction of air flow.

The air directing blade 46 is of a suitable shape and is provided with a hinge bar 47 which is 45 positioned centrally near the outer edge of the blade, as indicated. The free end of arm 45 is adapted to partly embrace the bar 47 and is provided with a similarly shaped pad 48 and holding bolt 49 whereby the pad may be tightened 50 sufficiently to hold the blade in a fixed position but permit it to be moved manually.

It will be noted that the outer edge and ends of the blade slightly overlap the openings provided for air passage through the decorative housing, whereby all of the air may be directed at will. It will be seen that the blade can be turned a 55 complete circle around the bolt 42 and that it may be moved to any desired angle while in any position around this circle, thus giving the operator complete control of the air as to the direction it will travel after it leaves the radiator core.

One of the advantages of applicant's air directing means is that there are but two manual 65 adjustments of the blade possible, one the angle of the blade and the other its position around a definite circle. Thus any person of normal intelligence will easily be able to secure any desired direction of air flow into the car.

Clearly the brackets 26 and 37 may be extended far enough to be directly attached to the motor. I prefer, however, to provide the intermediate plate as shown, which is attached to the bracket ends as at 27 and 38. These brackets are centrally positioned vertically (see Figure 2). An opening is provided in the plate, through which the motor bearing protrudes as indicated in Figures 1 and 2.

Various minor changes and position of parts 10 can obviously be made without departing from the spirit of my invention.

Having thus shown and described my invention, what I claim as new and desire to secure by Letters Patent is:

1. In a support for a heat exchange unit having a radiator core, upper and lower headers with central pipe receiving openings and a fan motor, comprising, upper and lower holding brackets, said brackets at their rear ends having outwardly projecting gusseted extensions with openings which register with said pipe openings and having means for holding said headers to said extensions, said brackets having a central longitudinal portion cut free except at one end, the free portions extending inwardly to thereby form upper and lower supports for said motor, the front ends of said brackets having vertically positioned gusseted extensions forming supporting feet therefor.

2. In a support for a heat exchange unit having a radiator core, upper and lower headers with central pipe receiving openings and a fan motor, comprising, upper and lower holding brackets each having at their rear ends outwardly projecting gusseted extensions with openings which register with said pipe openings and means for holding said headers to said extensions, two inwardly projecting spaced apart gusseted extensions on the front end of said upper bracket forming supporting feet therefor, an inwardly projecting gusseted extension on the front end of said lower bracket forming a supporting foot therefor, inwardly projecting arms on said brackets the ends of which are adapted to form upper and lower supports for said motor.

3. In a support for a heat exchange unit having a radiator core, upper and lower headers with central pipe receiving openings and a fan motor, comprising, upper and lower holding brackets, said brackets at their rear ends having outwardly turned gusseted extensions with openings which register with said pipe openings, and means for holding said headers to said extensions, said brackets having a central longitudinal portion cut free except at one end and extending inwardly to thereby form an upper and lower support for said motor, the front end of said upper bracket having two inwardly projecting gusseted extensions forming spaced apart supporting feet therefor, said lower bracket bent midway its length to thereby extend upwardly and forwardly and having a single upwardly bent gusseted extension at its front end forming a supporting foot therefor.

FRED M. YOUNG.
